Marvin Rainey

UNITED STATES PATENT OFFICE.

STANLEY H. MYSLINSKI, OF BROOKLYN, NEW YORK.

TRUNDLE AND HOOP.

Application filed April 14, 1924. Serial No. 706,231.

To all whom it may concern:

Be it known that I, STANLEY H. MYSLINSKI, citizen of United States, residing at Brooklyn, in the county of Kings and State 5 of New York, have invented certain new and useful Improvements in Trundles and Hoops, of which the following is a specification.

This invention relates to improvements in 10 hoops and more particularly of types used in playing outdoor games, known as grace hoops, because of the poise attained in its practice.

The main object of the invention is to provide 15 a hoop of attractive appearance that may be propelled, controlled and withdrawn, in connection with a stick of special formation, affording an amusement tending to render the player agile, graceful and compelling a wholesome exercise of the body.

Another purpose is to produce a sectional 20 hoop, capable of being dismembered when not in use, to facilitate storage and transportation.

Another aim is in the provision of a stick 25 having a neat appearing handle at one end and cranked elements at the other, carrying cushions for making contact with the hoop when in use.

These several aims and objects are accomplished by the novel construction and combination of parts hereinafter described and shown in the accompanying drawing, forming a material part of this disclosure, 30 and in which:—

Figure 1 is a perspective view showing an embodiment of the invention and illustrating its use.

Figure 2 is a fragmentary sectional view 35 showing the hoop elements engaging means, the view being greatly enlarged and taken in a plane at the longitudinal center of the hoop.

Figure 3 is a similar view of the same but 40 taken in a plane transverse to Figure 2.

Figure 4 is a perspective view showing the stick or driver in detail.

The hoop in its preferred form is composed 45 of two equal semi-circular sections 10 and 10', having radial, square cut ends, tightly abutting, when assembled, as at 11.

The preferred section of the hoop is that of a flattened ellipse, but it will be apparent 50 that any desired section may be used with equal effect.

Each of the hoop sections contain recesses

12 and 12' extending in register inward from their ends and fixed in the recesses 12 are rigid latch bars 13 reduced at their front extending ends 13' and held in rigid 60 relation by pins 14 set in the walls of the recesses.

The outer ends 13' of the latch bars are bevelled at one of their corners 15, rearward of which are notches 16 in their upper edges. 65

Tubular casings 17 pass transversely through the hoop sides 10', these casings being provided with slots through which the reduced ends of the latch bar pass, the casings having flanged heads 18 held to the 70 hoop elements by screws 19.

Slidable in the casings 17 are plungers 20 containing transverse slots 21, registerable with the recesses in the casings 17.

The inner ends of these slots are provided 75 with detents 22 engageable with the notches 16 of the latch bars and normally held in engaging position by springs 23 interposed between the ends of the plungers and bottom of the casings.

Said plungers have near their outer ends 80 slots 24 engaging pins 25, limiting the movement of the plungers, as best shown in Figure 2.

From the foregoing it will be seen that the 85 hoop may be separated into two equal parts by pressing the rounded outer ends of the plungers 20, releasing the latch bars 13; also that to connect the parts, the latch bars are merely entered into the corresponding 90 sockets and the hoop elements forced together.

The stick or controller is composed of a handle 26, convenient in shape and size to be grasped readily and extending from the 95 handle is a rigid rod 27 bent at a right angle 28 at its end, continued angularly rearward and downward at 29, formed into a crank 30 and terminating in a forwardly extending portion 31.

Loosely disposed on the elements 28 and 30 are sleeves 32 and 33 adapted to engage and press or pull the band without noise and with little friction, in the manner disclosed in Fig. 1.

Having thus described my invention, what I claim as new and desire to secure by Letters Patent, is:—

A play hoop comprised of two uniform semi-circular sections having recesses in 110 their abutting ends, latch bars fixed in oppositely disposed recesses to extend into the

remaining recesses, the hoop sections containing the remaining recesses being transversely bored, sleeves fixed in the mentioned bores, said sleeves being apertured to permit the passage of said latch bars, plungers in said sleeves through which the latch bars pass, said latch bars having notches on one edge with which elements of said plungers

may engage, springs in said sleeves pressing said plungers normally into engagement, 10 and means to prevent rotation of said plungers, said plungers being manually releasable.

In witness whereof I have affixed my signature.

STANLEY H. MYSLINSKI.
